UNITED STATES PATENT OFFICE.

JOHN S. HOLLIDAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

SIGNAL.

1,306,181.

Specification of Letters Patent. Patented June 10, 1919.

Continuation of application Serial No. 206,281, filed December 8, 1917. This application filed January 28, 1919. Serial No. 273,573.

To all whom it may concern:

Be it known that I, JOHN S. HOLLIDAY, a citizen of the United States, residing at Wilkinsburg, in the county of Allegheny 5 and State of Pennsylvania, have invented certain new and useful Improvements in Signals, of which the following is a specification.

My invention relates to signals, and particularly to signals of the type comprising a semaphore biased to a "stop" position and movable to a "caution" and a "proceed" position, a magnet for holding the semaphore in the caution position, and a relay responsive to reversals of current for controlling the supply of current to said magnet.

In signals of this character, when the semaphore is in the caution position and is to be moved to the proceed position, the 20 polarity of the current supplied to the relay is reversed, so that the relay is momentarily opened. This momentary opening of the relay causes momentary deenergization of the holding magnet, and unless means are 25 provided to prevent release of the armature of this magnet at such times, the semaphore will be released and will return to its stop position. This action of the semaphore has heretofore been prevented in various ways, 30 such as by making the holding magnet slow-releasing, or by interposing a slow-releasing relay between the controlling relay and the magnet.

According to my present invention, I provide a thermo-electric generator for supplying current to the holding magnet, and electrical means under the control of the controlling relay for heating the generator, so that during the momentary cessation 40 of current in such heating means incident to the reversal of the controlling relay the current supplied to the magnet by the generator does not decrease to the release value of the magnet.

The present application is a continuation 45 of my copending application, Serial No. 206281, filed December 8, 1917, for electro-magnetic apparatus, in so far as the subject-matter common to the two is concerned.

I will describe one form of signal and controlling apparatus therefor embodying my invention, and will then point out the 50 novel features thereof in claims.

The accompanying drawing is a view, partly diagrammatic, showing one form of signal and one form of controlling apparatus therefor embodying my invention.

Referring now to the drawing, the reference character S designates a semaphore which is pivotally mounted on a supporting mast or post 33. This semaphore is biased to the "stop" or horizontal position, as shown in solid lines, but may be moved to a "caution" or inclined position, and to a "proceed" or vertical position, as indicated in dash lines, these movements being accomplished by means of an electric motor M through the medium of suitable operating mechanism which I will now describe.

The operating mechanism comprises an arm 34 pivotally mounted at point 34^a in the frame of the mechanism and operatively connected with the semaphore S through suitable means indicated by the dash line 46. The arm 34 is moved by chains 37 and 37^a, which chains are in turn driven by the motor M in the direction indicated by the arrows. The chain 37 operates over two sprocket wheels 43 and 44, the first of these wheels being driven by the motor through a connection 25 which usually comprises reduction gearing. The chain 37^a operates over a sprocket wheel 45 and another sprocket wheel which is not shown in the drawing, but which is mounted directly behind the wheel 44 and is attached to the same shaft as the latter wheel. The chains 37 and 37^a are provided with rollers 38 which project laterally from the chains to engage with a fork 35 pivoted at point 35^a in arm 34. Two pairs of rollers are provided for each chain, the two pairs on each chain being disposed at diametrically opposite points on the chain. The fork 35 comprises three parallel prongs (only one of which is shown), the first and second of which coact with the rollers 38 on chain 37, and the second and third of which coact with the rollers on chain 37^a.

The fork 35 is controlled by an electro-magnet D through a toggle mechanism 36 in the arm 34, the control being such that the fork is held rigidly in the position shown with respect to arm 34, that is, in a projected position wherein it is in the path of rollers 38, when the magnet D is energized;

but is free to swing upwardly to a retracted position wherein it is out of the path of these rollers when the magnet is deenergized. It follows, then, that when the semaphore is in the stop position and magnet D is energized, if motor M is operated to drive the chain 37, one pair of rollers 38 on this chain will engage the fork 35 and so will elevate arm 34 and semaphore S to the intermediate or "caution" position, in which position the rollers will pass out from under the fork. The fork will then be caught and held by a latch 41, which is pivoted to the frame work of the signal mechanism and is biased to the latching position in which it is shown by a spring 41^a. If, then, the motor M is again operated, the fork 35 will be caught by one of the pairs of rollers on chain 37^a, so that the arm 34 and semaphore S will be elevated to the highest or "proceed" position, wherein the rollers will pass out from under the fork. The fork will then be caught and held by a latch 42, which latch is pivoted to the frame work of the mechanism and is biased to latching position by a spring 42^a. The semaphore will remain in this position until magnet D becomes deenergized, whereupon the fork 35 will swing upwardly with respect to arm 34 and so become disengaged from latch 42, so that the arm 34 and semaphore S will drop to their lowest positions, and the signal will again indicate "stop."

C designates a contact which is normally closed, but is opened by a knob 40 on arm 34 just before the arm reaches its highest position, that is, just before this arm is deposited on latch 42. The arm 34 actuates two other contacts 13 and 22 in the manner hereinafter explained in describing the operation of the signal.

The motor M and magnet D are controlled by current from a suitable source, such as a transformer T, the primary of which is supplied from a source of alternating current which is not shown in the drawing. The supply of current from the source to the signal is controlled by a relay R which is responsive to reversals of current. As here shown, this relay is of the polyphase motor type comprising two stator windings 2 and 3, a rotor 5, and a contact finger 4 operated by the rotor and biased to an intermediate or open position in which it is shown. Stator winding 3 is constantly supplied with current from the secondary of transformer T through connections which are apparent from the drawing, whereas stator winding 2 is reversibly connected with the secondary of transformer T by means of a pole-changer P. The currents in the two windings 2 and 3 are displaced in phase by any suitable means, such as by a reactance 8 in series with one of these windings. It is obvious that contact finger 4 will be swung

to the left or right, so that it will engage with fixed contact 6 or 7, according as the pole-changer P connects winding 2 with transformer T in one direction or the other.

The magnet D is supplied with current by a thermo-electric generator G, which generator may be of any suitable type. One set of the junctions of this generator, the left-hand set, as shown in the drawing, is subject to atmospheric temperature, while the right-hand set of junctions is at times heated by a resistance H, which is supplied with current in the manner hereinafter explained. When the resistance H is cold, so that both sets of junctions of the generator G are at the same temperature, no current is supplied to the magnet D, so that the latter is deenergized; but when the resistance H is hot, the generator G supplies sufficient current to the magnet D to cause this magnet to hold the fork 35 in engagement with rollers 38 or with latch 41 or 42.

The operation of the signal and of the controlling apparatus is as follows:

When the pole-changer P is in the intermediate position, as shown in the drawing, relay R is deenergized so that motor M and resistance H are both deenergized and the semaphore S is in the horizontal or stop position as shown, the other parts of the signal being also in the positions in which they are shown in the drawing. I will now assume that pole-changer P is shifted to energize relay R in such direction that contact finger 4 will swing to the left. Resistance H is then supplied with current from transformer T, the circuit being from the left-hand terminal of the secondary of this transformer, through wire 9, relay contact 4-6, wires 10 and 11, contact 23-22, wire 16, resistance H, and common wire O to the right-hand terminal of the secondary of transformer T. Resistance H is then heated, so that the thermo-electric generator G supplies current to the holding magnet D. Motor M is also supplied with current, the circuit being from the left-hand terminal of the secondary of transformer T, through wire 9, relay contact 4-6, wires 10 and 17, contact 12-13, wire 18, motor M, and common wire O to the secondary of transformer T. Motor M and magnet D both being energized, the arm 34 is raised by the rollers on chain 37, so that the semaphore S is moved to its intermediate or caution position. Just before the semaphore reaches this position, contact finger 13 is reversed by a cam 15 which is operatively connected with the arm 34, thus opening contact 12-13 and closing contact 13-14, so that the motor M becomes deenergized. Before the motor comes to rest, however, fork 35 is deposited on latch 41, so that the semaphore will be held in its caution position as long as magnet D con-

tinues to be energized, or until it is moved beyond this position, as I will now explain.

Contact 22-23 remains closed during the entire movement of the semaphore from 5 stop to caution positions and continues to be closed while the semaphore occupies the caution position. Just before reaching the latter position, however, a second contact 22-30 becomes closed and this contact continues to be closed while the signal is being moved to and while it occupies its vertical or proceed position.

I will now assume that pole-changer P is reversed, so that relay R becomes energized 15 in such direction as to swing its contact finger 4 to the right. A new circuit for resistance H is then closed, this circuit being from the left-hand terminal of the secondary of transformer T, through wire 9, 20 relay contact 4-7, wires 19 and 20, contact 30-22, wire 16, resistance H, and common wire O to the secondary of transformer T. The reversal of relay R also causes the closure of a new circuit for motor M, this 25 circuit being from the left-hand terminal of the secondary of transformer T, through wire 9, contact 4-7, wires 19 and 26, contact C, wire 27, contact 14-13, wire 18, motor M and common wire O to the secondary 30 of transformer T. Motor M, therefore, operates chains 37 and 37^a to lift arm 34 to its highest position, corresponding to the proceed position of the semaphore, and as soon as this position is reached the motor 35 is deenergized by the opening of contact C.

If, while the semaphore is in the proceed position, pole-changer P is returned to its intermediate or open position, relay R will become deenergized, so that the circuit for 40 resistance H will be opened. Magnet D will then become deenergized, whereupon the arm 34 and the semaphore S will drop to the positions in which they are shown in the drawing and the parts will then be 45 ready for a repetition of the operation hereinbefore explained.

If relay R should be reversed while the semaphore is moving between stop and caution positions, motor M will continue to operate on current supplied by the second circuit for this motor traced above, that is, through contacts 4-7 and C. Resistance H will be supplied with current through contact 4-31, wire 32, wire 11, contact 23-50 22, etc., until the semaphore reaches the caution position at which time the second circuit traced hereinbefore for this resistance becomes effective.

It will be noted that while the semaphore 55 is being held in the caution position, if the relay R is reversed to cause a movement of the semaphore to its proceed position, there is an interval of time during which the heating resistance H is deenergized, this being 60 due to the fact that the circuit for this re-

sistance is momentarily opened while the relay contact finger 4 is swinging from the fixed contact 6 to the fixed contact 7. If the magnet D were supplied with current directly from the transformer T, and this 70 supply were controlled by relay contact finger 4, it is obvious that the magnet D would be momentarily deenergized during this reversal of the relay, so that arm 34 would be released and would fall to its 75 lowest position, thus allowing semaphore S to return to its horizontal or stop position. The purpose of the thermo-electric generator G is to avoid this return of the semaphore S to its stop position during reversal of relay R. It is clear that during the reversal of the relay while the semaphore is in the caution position, resistance H will not have time to cool to atmospheric 80 temperature, so that the current supplied to magnet D will not decrease to zero during this interval. The generator G and resistance H may easily be so adjusted that during the interval in which the circuit for resistance H is opened by reversal of relay 85 R, the current supplied to magnet D will not decrease to the release value of this magnet.

My invention is particularly well adapted 90 for use in connection with signals which are operated by alternating current. As is well understood, when a tractive magnet is supplied directly with alternating current, such magnet cannot be made slow-releasing in action by the usual means, such as a copper 95 sleeve around the core of the magnet. If, however, the magnet is energized by current supplied by a thermo-electric generator, which generator is heated by the resistance supplied with alternating current, it is clear 100 that the armature of the magnet will not release until a certain time interval after the cessation of flow of the alternating current 105 in the heating resistance.

Although I have herein shown and described only one form of signal and controlling apparatus therefor embodying my invention, it is understood that various changes and modifications may be made 110 therein within the scope of the appended 115 claims without departing from the spirit and scope of my invention.

Having thus described my invention, what I claim is:

1. In combination, a semaphore biased 120 to one position, a magnet for holding said semaphore in another position in opposition to the biasing force, a thermo-electric generator for supplying current to said magnet, electrical means for heating said generator, and means including a relay responsive to reversals of current for supplying current to said electrical means when the relay is energized in either direction.

2. In combination, a semaphore biased to 130

one position, a magnet for holding said semaphore in another position in opposition to the biasing force, a thermo-electric generator for supplying current to said magnet, 5 electrical means for heating said generator, a source of alternating current, and means including a relay responsive to reversals of current for supplying energy from said alternating current source to said electrical 10 heating means when the relay is energized in either direction.

3. In combination, a semaphore biased to one position, a magnet for holding said semaphore in another position in opposition to the biasing force, a thermo-electric generator for supplying current to said magnet, 15 electrical means for heating said generator, a source of alternating current, a relay responsive to alternating current, means for reversibly connecting said relay with said source, and means controlled by said relay for supplying energy to said electrical heating means from said source when said relay is energized in either direction.

25 4. In combination, a semaphore biased to one position, a magnet for holding said semaphore in another position in opposition to the biasing force, a thermo-electric generator for supplying current to said magnet, 30 electrical means for heating said generator, and means including a relay responsive to reversals of current for supplying current to said electrical means when the relay is energized in either direction, said generator and 35 heating means being so adjusted that the current which is supplied to said magnet will not fall to the release value of the magnet while the supply of current to the heat-

ing means is discontinued during reversal of said relay.

5. In combination, a signal comprising a semaphore biased to stop position and movable to a caution and a proceed position, a magnet for holding said semaphore in caution and proceed positions, a thermo-electric generator for supplying current to said magnet, a resistance for heating said generator, 45 a relay responsive to reversals of current, and means controlled by said relay and by the signal for supplying current to said resistance to hold the semaphore in caution position when the relay is energized in either direction, and for supplying current to said resistance to hold the semaphore in proceed position when the relay is energized in one 50 given direction only.

6. In combination, a semaphore biased to one position, means for moving said semaphore to another position in opposition to the biasing force, a magnet for clutching said semaphore to said moving means while the semaphore is being moved and for holding the semaphore in the second position, a thermo-electric generator for supplying current to said magnet, electrical means for heating said generator, and means including a relay responsive to reversals of current for supplying current to said electrical means when said relay is energized in either 65 direction.

In testimony whereof I affix my signature in presence of two witnesses.

JOHN S. HOLLIDAY.
